(57) **CLAIM**

The ornamental design for a refrigerator, as shown and described.

DESCRIPTION

FIG. 1 is a perspective view of a refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the portion 8 in FIG. 1;

FIG. 9 is a front perspective view of FIG. 1 in alternate position;

FIG. 10 is a front view of FIG. 9;

FIG. 11 is a rear view of FIG. 9;

FIG. 12 is a left-side view of FIG. 9;

FIG. 13 is a right-side view of FIG. 9;

FIG. 14 is an top plan view of FIG. 9; and,

FIG. 15 is a bottom plan view of FIG. 9.

The even-dash broken lines illustrating portions of the refrigerator form no part of the claimed design. The dot-dash broken lines in the figures represent a boundary line and form no part of the claimed design.

A display device part of the refrigerator is rotatable to provide a portrait or landscape orientation of the display device part.

1 Claim, 15 Drawing Sheets
